UNITED STATES PATENT OFFICE.

FRED M. MOORE, OF SACRAMENTO, CALIFORNIA.

PISTON RING.

Application filed May 29, 1922. Serial No. 564,321.

To all whom it may concern:

Be it known that I, FRED M. MOORE, a citizen of the United States, residing at Sacramento, county of Sacramento, State of California, have invented certain new and useful Improvements in Piston Rings; and I do declare the following to be a full, clear, and exact description of the same, reference being had to the accompanying drawings, and to the characters of reference marked thereon, which form a part of this application.

This invention relates to improvements in piston rings such as are used in the pistons of gas engines, and is particularly an improvement over that type of ring shown in my copending application for patent filed May 24th 1922, Serial No. 563,234.

The principal object of the present invention is to produce a ring of the general type shown in the above mentioned application, that is, a floating and oil collecting ring which does not depend upon frictional contact with the cylinder walls to maintain a gas tight seal therewith, which will be more efficient in operation than the first shown type, will not wear the ring grooves, and is much stronger without any increase in cross sectional area of the ring.

30 A further object of the invention is to produce a simple and inexpensive device and yet one which will be exceedingly effective for the purposes for which it is designed.

35 These objects I accomplish by means of such structure and relative arrangement of parts as will fully appear by a perusal of the following specification and claims.

In the drawings similar characters of reference indicate corresponding parts in the several views:

Fig. 1 is a perspective view of the ring.

Fig. 2 is an enlarged cross section of the ring showing the same as mounted in its groove in a piston.

Referring now more particularly to the characters of reference on the drawings, the numeral 1 denotes the ring in general, of even thickness throughout, and preferably having its cut ends adapted to overlap horizontally as at 2.

Cut in the outer face of the ring, near the top is a continuous V-shaped groove 3, while cut in the lower face of the ring is another continuous V-shaped groove 4,

whose inner side extends parallel to the inner face of the ring and lies in a plane about midway of the width of the ring, and whose opposite side extends at an angle to meet the lower and outer edge of the ring. 60

Curved slots 5, eccentric with the ring-circle, are cut at spaced intervals in the inner face of the ring, in vertical alinement with the groove 4 but above the lower face of the ring somewhat, so that said lower 65 face is not cut into transversely, but retains a smooth and continuous surface. These slots or grooves 5 melt into the inner face of the ring at their ends, but centrally of their extent are of such a depth as to cut 70 through the inner face of the groove 4 and thus communicate with said groove.

This ring is preferably the lowermost one in the upper end of the piston 6, the latter having holes 7 leading from the interior of 75 the piston to the groove 8 therein in which the ring seats.

In operation, this ring functions in the same manner as the ring as set forth in the above mentioned copending application. 80 That is, as the piston descends, the groove 4 collects most of the oil previously thrown against the cylinder walls from the crank case of the motor. With the ascent of the piston, a tendency to vacuum is created in the crank case, which causes the oil in the groove 4 to be sucked therefrom, through the slots 5 and holes 7, into the interior of the piston, and thence back into the crank case with its body and lubricating qualities 85 unimpaired.

The ring is not definitely fixed in its groove, but floats, and with the oscillation of the pistons, constantly rotates. It is therefore not possible to maintain the holes 95 7 constantly in radial alinement with the slots 5, nor is this necessary, since the inner face of the ring is never snug against the back of the piston groove 8, and consequently a communicating space is always 100 had between the holes 7 and slots 5.

By reason of the under face of the ring having a continuous and unbroken surface, the rotation of the ring will not wear the lower face of the piston groove which I have 105 found to be a serious defect with the original ring in which radial slots or grooves were cut upwardly from the lower face of the ring, leaving sharp edges which produced a cutting effect on the lower face of 110

the piston groove due to the rotation of the ring. This soon resulted in the piston groove being too high for the ring, causing a ring-slap when the engine was in operation.

Further, I found that the former ring was weakened considerably by cutting these underside radial slots, and a tendency to breakage of the ring was increased, the fracture 10 always taking place at the said slots. These defects I have eliminated with the construction of the ring shown and described in the present application.

From the foregoing description it will be 15 readily seen that I have produced such a device as substantially fulfills the objects of the invention as set forth herein.

While this specification sets forth in detail the present and preferred construction 20 of the device, still in practice such deviations from such detail may be resorted to as do not form a departure from the spirit of the invention, as defined by the appended claims.

Having thus described my invention, what

I claim as new and useful and desire to secure by Letters Patent is:

1. In a piston ring, a groove cut in the lower face thereof and positioned with respect to the outer periphery of the ring to collect oil from the wall of the cylinder in which the piston moves, and arcuate grooves cut eccentric with the ring circle from the inner face of the ring intermediate the upper and lower faces thereof to meet and intersect the first named groove. 25

2. In a piston ring, a continuous groove cut in the lower face of the ring and extending upwardly and inwardly from the lower and outer edge thereof, and spaced grooves cut in the inner face of the ring above the 30 lower face thereof to communicate with the continuous groove, said second named grooves being longer at their inner ends than at their junction with said continuous groove. 40

In testimony whereof I affix my signature.

FRED M. MOORE.
